UNITED STATES PATENT OFFICE.

LORANCE DUNN, OF SAN FRANCISCO, CALIFORNIA, ASSIGNOR TO GEORGE O. JARVIS, OF SAN FRANCISCO, CALIFORNIA.

ELECTROTHERAPEUTIC APPARATUS.

Application filed October 6, 1924. Serial No. 741,807.

This invention relates to an electro-therapeutic apparatus for the treatment of various diseases and for experimentation in connection therewith.

5 An object of the invention is to produce an apparatus of such a type as to be capable of producing electrical vibrations capable of promoting the growth of healthy tissue.

10 Other objects of the invention will appear as the description proceeds.

An embodiment of the invention is shown in the accompanying drawings in which the same reference numeral is applied to the same portion throughout but we are aware 15 that there may be modifications thereof.

Figure 1 is a front elevation of the apparatus looking at secondary coils.

Figure 2 is a side elevation of the complete apparatus showing the magnet for operating the eddy current motor.

Figure 3 is an end view of the apparatus showing switches.

Figure 4 is a diagrammatic view of the circuit used.

25 Figure 5 is a smaller diagrammatic view of the primary windings, showing the manner of applying 110 or 220 volts to the apparatus without changing the apparatus or secondary output.

30 Figure 6 is a top plan view of the apparatus.

Figure 7 is a cross-sectional view on the line 7—7 of Fig. 1.

Beginning first with the electrical circuit shown in Figure 4, it will be seen that A is the primary of a transformer coil having the two wires a leading to any suitable source of alternating electric current, this particular apparatus being intended to be 40 used with 110 volt current.

Adjacent the coil A are several secondary coils B, one end of which coils is connected by the wire b to the coil core a', while the other end of the secondary coils is connected by wire b'' to the interrupter I, operated by 45 the motor M, which motor receives current from a small secondary coil MC. A condenser c is used in the wire c', while between the wire c' and c'' there is interposed in 50 parallel the adjustable condenser C and the single turn inductance D.

Two 1500 turn honeycomb wound coils E, E' are then placed in series between the wire c'' and wire e leading to the rheostat box R

containing a series of resistances r, any one 55 of which may be used.

The arrangement of the coils A and B is such that there is a difference of potential of 3000 volts from b to b'' and a series of taps b' allow lower voltages to be used if desired.

60 If it is desired to make use of 110 or 220 volt circuits, the primary coil is divided up as shown in Figure 5. In this figure the letter P indicates four coils forming the primary, the motor coil being shown at m' c'. 65 Switches S S' are arranged to be connected to the 110 or 220 volt circuits as may be desired to give the same results on the secondary as with the coil A at 110 volts.

The apparatus used is shown in Figs. 1 to 70 3 and consists of a base board 1 on which is mounted a pair of low frames 2 and 3 to support a rectangular laminated soft iron core 4 carrying four primary coils 5 to 8, the motor coil 9 and a plurality of secondary 75 coils 10, twelve of them being used in the present apparatus.

75 Mounted on the core 4 are four posts 11 to 14, the posts 12 and 14 being connected by a board 15 carrying a plurality of binding 80 posts 16. The posts are connected to the plates 2 and 3 by the bolts 17 to 20 passing through the inturned bottom flanges of the posts. The posts are also connected by two cross bars 21, 21', a switch board 22, as well 85 as by a rectangular frame 23 at the top of said posts.

The two bars 21, 21' are made of channel form and support a slide 24 which can be pulled out or pushed in by the handle 25 90 to place the electromagnet 26 at any desired point to regulate the rotation of the plate 27 on the shaft 28. The plate passes in close proximity to the end of the magnet core 29 as well as in close proximity to the 95 edges of a series of soft steel plates 30 supported by the frame 23 slightly above the plate 27.

The frame braces 21, 21' carry a cross channel 31 which supports a bearing 32 for 100 the lower end of the shaft 28, said bearing being adjustably held by screws 33, 34 and 35.

The shaft 28 supports a contact plate 36 on the top of an insulating block 37; said 105 shaft also passing through a bearing 38.

Supports 39, 40 carry a rod 41 of some insulating material and said rod carries two

spring contacts 42, 43 with which the plate 36 periodically contacts.

At one end of the board 1 there are two posts 50, 51, which carry a rod 52 which supports two ordinary honeycomb coils 60, 61 of 1500 turns each, on opposite sides of a flat frequency transformer coil 53 having about three turns.

On the base 1, and only diagrammatically shown, is a small fixed condenser 54 and a variable condenser 55.

The manner of wiring has been indicated above the corresponding parts being numbered as follows:

- 15 Primary coils A are 5 to 8.
- Secondary coils B are 10.
- Motor coil MC is 9.
- Motor M is 27.
- Interrupter I is 36.
- 20 Small fixed condenser c is 54.
- Adjustable condenser C is 55.
- Flat coil D is 53.
- Two coils E, E' are 60, 61.

The non-inductively wound resistances on the board R form no part of the present apparatus and are merely used to connect the patient with the current of the desired vibratory effect, ordinary sheet metal electrodes being placed on the body to effect the desired results.

For the convenience of the operator switches 62, 63, 64 may be installed on the board 22 to have the means for the control of the apparatus at hand.

35 When it is desired to use the apparatus, either the 110 or 220 volt circuit may be impressed on the primary coils. This energizes the system and causes high frequency electrical impulses to be given off from the

40 electrodes which may be connected with

them. The kind of a current used (in frequency) being determined beforehand from other apparatus, and the treatment may be regulated as to time as may appear needed.

What I claim is as follows, but modifications may be made in carrying out the invention shown in the drawings and in the above particularly described form thereof within the purview of the invention as defined by the annexed claims:

1. A therapeutic apparatus comprising means for stepping up commercial to high voltage, having circuit wires extending therefrom, one of which wires is grounded, a mechanical circuit breaker interposed to the other wire, a condenser to which the latter wire is connected, a wire extending from the first condenser to another condenser, and frequency transformer in parallel, and induction coils connected to the treatment apparatus, and supports for said coils, permitting them to be adjusted toward and from the frequency transformer.

2. A therapeutic apparatus comprising means for stepping up commercial to high voltage, having circuit wires extending from the secondary, one of which wires is grounded, a mechanical circuit breaker interposed in the other wire, a condenser to which the latter wire is connected, a wire extending from the condenser to a second condenser and frequency transformer in parallel, and movable induction coils supported on opposite side of the frequency transformer; said coils being connected in series and to the treatment apparatus.

In testimony whereof I have hereunto set my hand this day of September A. D. 1924.

LORANCE DUNN.
